2 Sheets-Sheet 2

UNITED STATES PATENT OFFICE.

HENRY J. SHAVERS, OF GOLDSBORO, NORTH CAROLINA.

LUBRICATOR.

Application filed October 31, 1921. Serial No. 511,771.

To all whom it may concern:

Be it known that HENRY J. SHAVERS, a citizen of the United States, residing at Goldsboro, in the county of Wayne and 5 State of North Carolina, has invented certain new and useful Improvements in Lubricators, of which the following is a specification.

My invention relates to new and useful 10 improvements in lubricators that are especially designed to force heavy oil and graphite to the cylinders of a locomotive.

The present invention is somewhat similar 15 in type to the lubricator shown in Patent No. 1,384,353, granted to me on July 12, 1921.

In the patent just above mentioned the oil and graphite were placed in one main reservoir and then forced by the same means 20 to the cylinders of the locomotive, while in the present instance separate reservoirs are provided for the reception of the oil and graphite and separate means are provided for forcing the oil and graphite to the cylinders of the locomotives.

One of the objects of the present invention is to provide a lubricator wherein the graphite will be continuously under a slight pressure and will be constantly agitated in 30 the reservoir by a revolving blade which is designed to scrape the lower sides of the reservoir so that the graphite may be properly fed to the regulating means which is located just below the blades, this regulating means determining the amount of graphite to be fed to the cylinders by each stroke of the plungers of the lubricator.

Still another object of the present invention is to provide this regulating means in 40 the form of a rotary shaft which is placed beneath the graphite chamber, this shaft having formed therein oppositely disposed pockets for the reception of the graphite from the reservoir which pockets in turn 45 permit the discharge of the graphite to the plungers of the cylinders, the shaft being in synchronism with the said plungers.

Still another object of the invention is to 50 form this shaft with the disposed pockets mentioned and to provide passage ways extending laterally to these pockets, in which are placed regulating tubes which are capable of adjustment so that the capacity of the pockets may be made greater or less de-

pending upon the amount of advance or re- 55 fraction of these tubes.

Still another object of the invention is to provide means for supplying oil to the cylinders of the locomotive which may be used in conjunction with the flow of graphite or may be used in an auxiliary manner.

With these and other objects in view, the invention consists of certain new and novel arrangements and combination of parts as will be hereinafter more fully described and 65 pointed out in the claims.

Referring now to the drawings showing a preferred form of the invention:

Fig. 1 is a side elevation of my improved lubricator, parts being shown in section and 70 others in elevation,

Fig. 2 is a vertical sectional view taken on line 2—2 of Fig. 1 looking in the direction of the arrows, some of the parts being shown in elevation,

Fig. 3 is a detailed sectional view of the 75 regulating shaft and

Fig. 4 is a top plan of the main driving crank, the outer sprocket being shown in section.

Referring now in detail to the several figures, there is shown a base 1, on which is mounted a motor 2, although it is to be understood that any form of driving means may be employed. A standard 3 is shown 80 in which is mounted the crank shaft 3' on which is mounted the worm gear 4 which in turn is driven by the worm gear 5 on the motor shaft. A sprocket 5' is mounted at one end of the crank shaft 3 as clearly 85 shown in Fig. 4.

Two crank arms 6 are operated by the gear 4 to which crank arms are in turn secured the connecting rods 7, the same in turn being pivotally mounted to the cross head 8, 90 which is mounted on the sliding bar 9.

This sliding bar is supported at one end by the standard 10 and at its other by the main housing 11 of the lubricator.

This housing 11 is in turn supported by 100 the brackets 12 which are bolted to the base 1 as clearly shown in Figs. 1 and 2.

Mounted in this housing are the two cylinders 13 and 14 to which are bolted the heads 15 and 16, and as the cylinders and heads 105 and cooperating plungers are identical a description of one will suffice.

Referring now in particular to Fig. 1 it

will be seen that the head 16 extends inwardly for a greater portion of the cylinder, and is provided with the rings 17, and is beveled at its inner end, and provided with the projecting portion 18.

Within this cylinder is the hollow plunger 19 which is provided with the upper or inlet port 20 and with the larger outlet port 21 formed in its under surface. Connected to this plunger is the rod 22 which extends through its cylinder head 23 and the gland 24 and is fastened to the heretofore mentioned sliding head 8.

This hollow plunger snugly fits the head 16 so that when the same is operated it will compress the air in the plunger on its forward stroke and form a vacuum on its rearward or return stroke.

Extending through the lower portion of the cylinder is the port 25 and directly beneath the same is the check valve 26 secured in turn to the coupling 27 in one side of which may be secured a jet pipe 28 while another pipe 29 leads to the cylinder of the locomotive. Also leading to this coupling 27 (Fig. 2) is the pipe 30 which is from the oil feed as will be hereinafter described.

As far as the description has proceeded it follows exactly the construction shown in my former patent with one exception, that is, on the main crank shaft there is mounted the sprocket 5' as heretofore mentioned and the purpose of which will be shortly described.

Referring now to Figs. 1, 2, and 3, it will be seen that bolted or otherwise secured to the housing 11 is the graphite reservoir partly in the form of a cylinder 31, in which is provided the small piston head 32, and in a cylinder head 33 is secured a small pipe 34 for the admission of a slight amount of steam or air pressure. A packing gland 35 is also secured centrally to the head 33 through which extends the tube or hollow shaft 36, on which is mounted the heretofore mentioned piston head 32. This hollow shaft and piston are slidably mounted on a main vertical shaft 37 which extends from the lower end of the reservoir and to the standard 38 and is provided near its upper end with a beveled gear 39 which in turn meshes with the gear 40 which is mounted on a stub shaft 41, said shaft being suitably mounted in the bearings 42 formed on the upper part of the standard 38, and a small sprocket 43 is mounted on the stub shaft as shown in Fig. 2. To the lower end of the vertical shaft 37 are secured the vanes or blades 48 which extend parallel with the lower inner side walls of the reservoir, these walls being beveled or truncated as clearly shown in the separate figures. The lower end of the shaft 37 may be notched as at 49 to also assist in cutting or disintergrating the graphite.

A main discharge opening 50 is provided centrally of the reservoir and at its bottom extending laterally through the base of the reservoir is the bearing 51 in which is rotatably secured the regulating shaft 52, which is provided with a slightly enlarged central portion 53 in which is disposed the oppositely disposed pockets 54 and 55. Two passage ways 56 and 57 are shown which respectively extend from the outer ends of the shaft to the pockets which passage ways are angularly disposed to the central axis of the shaft. These passage ways are internally threaded for the reception of the regulating tubes 58, one being shown in an advanced position in Fig. 3.

The purpose of these regulating tubes is that when they are advanced the capacity of the pocket will be less than when the tube is retracted.

Lock nuts 59 are provided so that the tubes may be held in an advanced or retracted position. Small check valves 60 are provided on the outer ends of these tubes so that air may be drawn through in the tube, but cannot be forced therethrough.

On this regulating shaft there is provided two sprockets 61 and 62, the sprocket 61 carrying a chain 63 which passes over the sprocket 43 mounted on the stub shaft 41 while the outer sprocket 62 is driven by a chain 65 extending to the sprocket 5' on the crank shaft 3'.

The outer sprocket 62 and the sprocket 5' are each provided with the requisite number of teeth, so that a complete forward and rearward stroke of the plungers will cause a complete revolution of the regulating shaft 52.

Located just below the regulating shaft 52 is a further lateral passage 66 provided with slight glasses at each end so that the discharge of graphite may be seen and regulated.

As far as the specification has proceeded it will be seen that when the lubricator is in operation the vertical shaft 37 with the blade 48 thereon will be constantly revolved as well as the rotatable regulating shaft 52, and as one of the pockets register with the opening 50 of the reservoir it will be filled with graphite and then revolved to the discharge position where the suction caused by the rearward stroke of the plunger will draw the graphite from the pocket down into the hollow plunger, this being made possible by having the regulating tubes hollow and provided with check valves to allow a slight amount of air to be drawn with the graphite.

If a less amount of graphite than the capacity of a whole pocket is desired, the tubes will be advanced to thereby lessen the capacity of the pockets.

Referring now to the means of furnishing the oil to the cylinders, it will be noticed

that the reservoir 31 is provided with the opening 70 and plug 71 at its bottom, and the opening 72 and plug 73 at its top and with a central inlet passage 74 which registers with the discharge opening 75 of a condenser 76. A pipe 77 is threaded into the top of this chamber 69 and extends nearly to the bottom thereof while the main discharge for the oil chamber is at 80, 10 these discharge openings being located in the top of the chamber.

From these openings leads the pipes 82 which in turn extend to eight chambers 83 which are provided with valves 84 while 15 from the top of these chambers are the elbows 85 which are connected to the pipes 30, heretofore described which extend into the couplings 27.

Oil will be placed in the chamber 69 and 20 as the water or condensation arises in the chamber, the oil flowing to the top will be forced out through the outlets or opening 80 to the chambers 83 which will also become filled with water and the oil may then 25 be noticed as it passes through the water to the pipes 85 and to the couplings 27. This is the usual practice of feeding oil to the cylinders of a locomotive. Separate arms 86 are shown bolted to the main casing for 30 supporting these eight chambers.

The arrangement and operation for feeding the desired amount of graphite has been set out and it is to be understood that the oil will generally be fed to the cylinders in 35 junction with the graphite.

From the foregoing it will be seen that the desired amount of graphite to be fed to the cylinders may be quickly and easily regulated and as a complete stroke of each 40 plunger is made a complete revolution of the shaft will be made so that the graphite will be first forced into the upper pocket of the shaft 52, which pocket will be then revolved to its discharge position, the return stroke 45 of the plunger causing the vacuum which will draw the graphite into the plunger. Again on the forward stroke of the plunger it will force the graphite into the main pipe extending to the locomotive cylinders 50 and at the same time revolve the pocket to a receiving position.

The revolving blades agitates the graphite at all times and insures the constant and proper feed to the pockets. Also by providing hollow regulating tubes a sufficient amount of air is admitted to the pockets so that the graphite may be withdrawn therefrom by the rearward action of the plungers, and the amount of graphite may be regulated according to the set position of the tubes.

Many slight changes might be made in the arrangement and positioning of the parts without in any way departing from the spirit and scope of the invention.

Having thus described my invention what I claim as new and desire to secure by Letters Patent is:—

1. A lubricator comprising a base, a cylinder on said base, a hollow plunger in said cylinder, said plunger provided with an inlet and outlet port and an inlet and outlet port in said cylinder, a reservoir for the lubricant forming a part of the lubricator and means for agitating the lubricant in the reservoir, means for forcing the plunger inwardly and outwardly to draw the lubricant in said plunger, compressing the air in said plunger and forcing the same with the lubricant from the plunger to the parts to be lubricated.

2. A lubricator comprising a base, a cylinder on said base, a hollow plunger in said cylinder, said plunger provided with an inlet and outlet port and an inlet and outlet port in said cylinder, a reservoir formed integral with the cylinder for the lubricant, a blade in said reservoir for agitating the lubricant, means for revolving said blade, means for forcing the plunger inwardly and outwardly, to draw the lubricant into said plunger, compress the air in said plunger and force the same with the lubricant from the plunger to the parts to be lubricated.

3. A lubricator comprising a base, a cylinder on said base, a hollow plunger in said cylinder, said plunger provided with an inlet and outlet port and an inlet and outlet port in said cylinder, a reservoir for the lubricant vertical shaft in said reservoir and provided with blades for agitating the lubricant, means for forcing the plunger inwardly and outwardly to draw the lubricant into said plunger, compress the air in said plunger and force the same with the lubricant from the plunger to the parts to be lubricated, and means connected to the shaft and to the means for forcing the plunger inwardly and outwardly, to revolve said shaft.

4. A lubricator comprising a base, a cylinder on said base, a hollow plunger in said cylinder provided with an inlet and outlet port and an inlet and outlet port in said cylinder, a reservoir for the lubricant, rotatable means positioned between the reservoir and the plunger for receiving and dispensing the lubricant, hollow adjustable means having a check valve located on its outer end thereof, said means regulating the amount of lubricant to be received in the rotatable means, means for forcing the plunger inwardly and outwardly to draw the lubricant from said rotatable means into said plunger compress the air in said plunger and force the same with the lubricant from the plunger to the parts to be lubricated.

5. A lubricator comprising a base, a cylinder on said base, a hollow plunger in said

cylinder, provided with an inlet and outlet port and an inlet and outlet port in said cylinder, a reservoir for the lubricant, a shaft provided with pockets for receiving and discharging the lubricant, tubes adapted to be extended into and withdraw from said pockets to limit the capacity of said pockets, means for revolving said shaft in synchronism with said plunger so that the 10 discharge pocket in said shaft will register with the inlet port of said plunger on the rear stroke of said plunger, means for forcing the plunger, compress the air in said plunger and force the same with the lubricant from the plunger to the parts to be lubricated.

6. A lubricator comprising a base, a cylinder on said base, a hollow plunger in said cylinder provided with an inlet and outlet port and an inlet and outlet port in said cylinder, a reservoir for the lubricant, a vertical shaft in said reservoir and provided with vanes at its lower end for agitating the lubricant in said cylinder, a rotatable shaft 20 located beneath said reservoir and provided with oppositely disposed pockets for receiving and discharging the said lubricant, tubes extending into said pockets and adapted to be moved inwardly and outwardly of 25 said pockets to regulate the capacity of said pockets, means for forcing the plunger inwardly and outwardly to draw the lubricant into said plunger, said rotatable means being connected to said means for operating

the plunger so that said rotatable means and said plunger will operate in synchronism, means connected with said rotatable means and with said vertical shaft in said cylinders for operating the vertical shaft in said cylinders, said plunger on its rear 35 stroke adapted to withdraw the lubricant from the said rotatable means into said plunger and on its forward stroke compress the air in said plunger and force the same with the lubricant from the cylinder to the 40 parts to be lubricated.

7. A lubricator comprising in part a rotatable shaft having oppositely disposed pockets therein, angularly positioned passage ways extending into said pockets and 45 hollow tubes to regulate the supply of air in said passage ways and adapted to be extended into and withdrawn from said pockets to limit the capacity of said pockets.

8. A lubricator comprising in part a rotatable shaft having an enlarged central portion and oppositely disposed pockets therein, passage ways extending to each of the said pockets and to the outer ends of 50 said shaft, tubes fitting within said passage ways and adapted to be extended to a desired distance into said pockets to limit the capacity thereof, means for holding the tubes in a set position and said tubes being 55 provided at their outer ends with check valves.

In testimony whereof I affix my signature.
HENRY J. SHAVERS.
